INVENTOR.

Frederick S. Bosworth

UNITED STATES PATENT OFFICE.

FREDERICK S. BOSWORTH, OF PROVIDENCE, RHODE ISLAND, ASSIGNOR TO
THE WEYBOSSET MILLS, OF SAME PLACE.

DESIGN FOR FANCY CASSIMERES.

Specification forming part of Design No. **8,052**, dated February 9, 1875; application filed January 18, 1875.
[Term of Patent 3½ years.]

To all whom it may concern:

Be it known that I, FREDERICK SNOW BOSWORTH, of the city and county of Providence, in the State of Rhode Island, have invented a certain new and useful Design in Fancy Cassimere Fabrics; and I do hereby declare that the following specification, taken in connection with the drawings making a part of the same, is a full, clear, and exact description thereof.

The peculiar optical effect of my design is based upon the novel character of the composite stripe A, and said effect is attainable independently of any accompanying lines or figures. In said stripes, the prominent or ruling feature is presented in the four diagonal lines, which intersect with each other alternately at top and bottom, so as to present, at intervals, figures resembling the letter **W**. The secondary feature is presented in the several transverse bars *a*, located between each

of the aforesaid ruling figures. These bars serve to effect a marked separation of said figures.

These composite stripes A may be employed with or without accompanying lines, stripes, and figures, and with plain or fancy woven grounds.

Colors constitute no essential feature of said design, provided that sufficient contrast is attained to develop the characteristic features thereof, and produce the optical effect sought in designs of this general character.

What I claim as my invention, and desire to secure by Letters Patent, is—

The design for fancy cassimere fabrics, as herein set forth and represented in the drawings.

FREDERICK SNOW BOSWORTH.
